Primary Examiner — Ryan Harvey

(57) **CLAIM**

The ornamental design for a multifunction exercise apparatus, as shown and described.

DESCRIPTION

FIG. 1 is a front, top perspective view of a multifunction exercise apparatus, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the portion labeled 8 in FIG. 1; and,

FIG. 9 is an enlarged view of the portion labeled 9 in FIG. 1.

The broken lines in the drawings depict portions of the multifunction exercise apparatus that form no part of the claimed design.
